UNITED STATES PATENT OFFICE.

JAY B. WALKER, OF PEORIA, ILLINOIS, ASSIGNOR TO HADBURY HEATER COMPANY, OF PEORIA, ILLINOIS.

HOT-WATER BOILER.

No. 823,981.

Specification of Letters Patent.

Patented June 19, 1906.

Application filed February 6, 1905. Serial No. 244,394.

To all whom it may concern:

Be it known that I, JAY B. WALKER, a citizen of the United States, residing at Peoria, in the county of Peoria and State of Illinois, have invented certain new and useful Improvements in Hot-Water Boilers; and I do hereby declare that the following is a full, clear, and exact description of the invention, which will enable others skilled in the art to which it appertains to make and use the same.

This invention pertains to water-heaters for use in heating buildings, and has for its object to provide a heater of simple construction and one that can be readily cleaned and also one that affords but little lodgment for soot and ashes.

A further object of the invention is to provide a heater of the class described wherein all of the heating-surfaces are easily kept free of soot and ashes, so that practically none of such heating-surface is lost.

A further and important object of the invention is to secure in the heater as large an amount of water-space as possible, so that all heated surfaces may be put to the greatest use possible.

Another object is to surround the fire on all sides and at the top with water, so that greater heated surface for the circulating water may be had.

Another object of my invention lies in the provision of a removable water-front by which the interior of the heater may be easily reached and also by which heaters of varying size may be readily built up and provided with a water-front suitable thereto.

A still further object of the present invention is to furnish a new and simple manner of mounting the sections of the grate, whereby they may be readily and easily removed and replaced, as desired.

In addition to these several objects certain details of construction will be described in the following specification, the advantages of which will be readily seen.

In the accompanying drawings, forming part of this application, Figure 1 is a perspective view of one size of my improved heater. Fig. 2 is a side elevation of the heater with an outside section removed and showing certain parts in section. Fig. 3 is a front elevation of the heater with the entire front removed. Fig. 4 is an elevation of the inner side of an

outside section of the heater. Fig. 5 is a horizontal section of the heater on line X X, Fig. 2. Fig. 6 is a perspective view of a portion of the front water-leg, illustrating notched ledges for receiving the grate-bars. Fig. 7 is a perspective of portions of the sections of the heater, showing recesses for the reception of the opposite ends of the grate-bars. Fig. 8 is a perspective view of a "manifold" for connection with all of the water-sections of the heater.

In the figures, A represents the base of the heater, which is merely the usual ash-receiver below the fire-box, to be described. Said base is provided with the usual door B for withdrawing the ashes, and above and resting upon the base is a series of vertical sections C C and C' C', the former of which are the outside members and the latter being placed between them, as shown in Fig. 3. The form of the members C' is shown in Fig. 2. The top and back surfaces are at right angles to one another, and the front near the top is substantially parallel with the back surface and extends downward for a short distance, where it meets the front water-leg D, to be described later. From this point of meeting with the front the said member is recessed to form the fire-space, and therefore extends back and downward in an ogee form, substantially as shown, and thence drops vertically to the grate, the latter being illustrated in Fig. 4. Each side of the section is provided with a groove or depression E in front and a similar depression F at the rear, separated from each other for the greatest part of their length by a middle flange G, created by forming the said depressions, said flange being flush with a similar flange at the rear (represented by H) and one at the front J, the former forming the rear wall of the section and the latter the surface above the fire-space against which the heat impinges.

The flanges H and J extend forward and downwardly and upwardly, respectively, leaving between them an opening K for cleaning out the depressions from the front, if desired. The openings thus created between each of the sections form the holes illustrated in Fig. 3 and one of which is also shown in Fig. 1. A plate L covers the front of the sections at the top, in which holes M, one of which is shown in Fig. 2, are provided and covered by removable plates or doors N. The middle

flange G curves upward and forward, following somewhat the contour of the outer surfaces of the section and ends opposite and somewhat back from the openings K described, so that the depressions E and F communicate with one another, as shown. The former one, E, opens at E' into the fire-space, as shown, and the lower end of F opens through the back of the section into a common smoke-chamber. It will thus be seen that the products of combustion must enter at the bottom of the passage E, pass upward and forward, and thence backward and downward to the bottom of F before they are liberated. Each side of each section C' is thus formed, so that when two or more of them are placed side by side closed passages are created, as will be understood by reference to the figures, especially Fig. 5, the abutting flanges G separating them, as described. In addition to the above, openings P and Q are made in the grooves E and F, respectively, so that circulation of heat may take place between all of the sections of which the heater may be composed, thereby insuring an even heating of all the surfaces of the entire device. The said openings P and Q are formed in the arcs of circles of different size, which, however, is immaterial; but they conform substantially with the direction in which the depressions E and F extend, as offering the least friction to the passage of the products of combustion.

Where practicable, the interior of the sections are made hollow for water-space, these spaces being indicated as shown by dotted lines in Fig. 2, also being partially shown in cross-section in Fig. 5. The outer sections C C are provided with grooves or depressions E² and F² to correspond with E and F of the intermediate section; but the holes or openings P Q of the latter are lacking, as Fig. 4 will show. In other respects the said outer sections are the same as the inner ones. However, as shown in Figs. 4 and 5, the said outer sections are provided with water-legs R, made integral therewith, and these constitute the sides of the fire-space, forming, in other words, part of the fire-box. The inner fire-surface of these legs are corrugated, as shown, in order to prevent warping of the leg by the intense heat and also to provide greater heating-surface. These sections C provide a solid water-space, as shown in Fig. 5, which communicates with the water-spaces of the inner sections by pipes S and equalizer T at the tops of the sections and by means of pipes U and a manifold V beneath the sections. The latter is merely a hollow member, with which all of the sections communicate and into each end of which are connected the pipes W, which are the returns from the radiators. The pipes T' on the equalizer T are the outlets for the hot water to the radiators, as will be understood.

The front water-leg D, mentioned hereinbefore, is clearly shown in Figs. 2 and 5, merely consisting of a flat box having an opening at D' for the fire-door, the bottom of which rests upon the bottom member A, the top being adapted to fit the undercut recess of the sections C', Fig. 2, it being understood that the outer sections C are also undercut for the same purpose, this being seen in Figs. 3 and 4, the shading in the former figure indicating the recesses extending entirely across the sections, and in this figure it can be readily seen that the addition of the front D will supply the last member to completely inclose the fire-space. Though not shown, bolts or other suitable devices are employed to secure the various members together to form a complete whole, with which any desired packing may be used to make all joints perfectly air and gas tight. Equalizing-pipes 2 and 3 connect the front D with the outer sections C, so that free circulation of water can result.

At the bottom of the sections and between them are recesses 4 for receiving the ends of the grate-bars 5. This is clearly shown in Figs. 2, 4, and 7, the recesses being constituted by casting a recess or notch in each side of each section, so that when placed together an inclosure is the result, which leaves a ledge 6, upon which the ends of the said bars 5 rest. Just opposite these recesses, on the bottom of the front leg D, are cast lugs 7, each of which has a depression 8 therein, in which the opposite ends of the bars rest. By this construction the entire grate may be removed from the heater or replaced at will. In doing so the bars are reached through the fire-door, the ends of the bars at the front being raised and then withdrawn from the recesses 4 or replaced by first entering the said recesses and then dropping them into the notches in the lugs.

To my knowledge heaters have not heretofore been constructed like mine, nor do they have the advantages of my construction. By having the front water-leg separately made and removable the interior is readily reached when necessary. Further than this it will be seen that when more sections than shown in the drawings are employed a water-front of the proper size may be set in place to just fill the requirements. The peculiar tortuous passage for the smoke, in addition to the openings P and Q in said passages, give a very large area of heating-surface. While I am aware that it is not new to entirely surround the fire with water, yet the peculiar construction herein shown and described is new, coupled with the advantage of the removable front above described. I also believe it to be new to provide the means described for supporting the grate-bars and making it easy to withdraw or replace them. It will be observed that the soot may be read-

ily removed from the passages by inserting a brush through the front opening K or up through either of the openings at the bottom of the passages E F. Any soot or ashes lodging upon the flanges G can be easily pushed off through said opening K, and the openings P and Q can be reached from the same opening. I have just stated that any soot lodging within the passages can be readily removed by means of a brush. As a matter of fact the places of lodgment are so little that the soot will usually readily fall either into the fire-space or into the smoke-chamber O. This is particularly evident from a study of Fig. 2, wherein the flange G is formed in the arc of a circle, leaving little or no place for lodgment of soot or ashes. It is well known that by having the smoke-passages in heaters of short length and close to the fire the soot will be kept burned off, and the draft being stronger by reason of the short passages and their close proximity to the heat aids in keeping such passages cleared. As many sections C' may be employed as desired, these always being inclosed by an outer section C and a front water-leg D of sufficient size being used to cover the whole.

Having thus described my invention, I claim—

1. A hot-water boiler comprising a series of hollow water-containing sections mounted side by side and adapted for intercommunication of water, end members for forming the side of the fire-space and a hollow water-containing member at the front of the sections and having the fire-door therein.

2. A hot-water boiler comprising a series of hollow water-containing sections mounted side by side and adapted for intercommunication of water, end members for forming the inclosing ends of the fire-space, a hollow detachable water-containing member at the front of the sections having the fire-door therein and water connections between the said member and the sections.

3. A hot-water boiler comprising a series of hollow water-containing sections mounted side by side and arranged for intercommunication with one another, the end sections inclosing and forming the side of the fire-space, and a hollow water-containing member detachably secured in front of the sections, the same extending the full height of the fire-space and having the fire-door therein, said member having water connection with the said sections, substantially as set forth.

4. A hot-water boiler comprising a series of adjoining and communicating hollow water-containing sections, each pair thereof having a single upwardly and then downwardly extending smoke-passage curved in the arc of a circle as shown, the sections being undercut to form the fire-space, the end sections constituting the inclosing members of the fire-space, a hollow water-containing

member removably secured at the front of the apparatus and extending from the upper projecting front of the sections to the bottom of the fire-space and entirely closing the front of said fire-space as shown and having the fire-door therein and members for permitting water communication of the front member with the sections.

5. A hot-water boiler comprising a series of hollow water-containing sections adjoining and communicating, the same being undercut to form the fire-space, the end sections forming the inclosing walls for said fire-space, a front water member extending from the top front extension of the sections to the bottom of the fire-space and entirely inclosing the latter space, the said sections being cut out to receive the top of the said front member, said latter member having the fire-door opening therein, pipes for connecting the front member with the sections, and means for permitting intercommunication of all of the sections substantially as set forth.

6. A hot-water heater comprising a series of intermediate separable, hollow, inverted substantially L-shaped water-containing members each having a depression in each side, a flange following the contour of the outer edge of each said section at each side thereof for creating the said depressions, a flange dividing each depression into two portions, said flange being formed in a continuous curve in an upward and downward direction as shown, said flange extending toward the bottom of the section, there being a recess in the surrounding flange forward of the dividing-flange substantially as shown, there also being a recess in the back of the said surrounding flange behind the dividing-flange, there also being a hole through the sections at each side of the dividing-flange, an opening in the forward portion of the surrounding flange opposite the upper termination of the said dividing-flange, a hollow water-containing section at each side of the intermediate sections to form the ends of the boiler, said end sections forming the inclosure for the fire-space, and corrugations within the fire-space as shown and for the purposes set forth means for interconnecting all of the sections for intercommunication of water, and a front hollow water-containing member inclosing the fire-space in front thereof, the same extending the full height of the said space and having the fire-door opening therein, there being means also for connecting such member by water connections with the sections substantially as described.

7. A hot-water heater comprising a series of intermediate separable, hollow inverted L-shaped water-containing members each having a depression in each side, a flange following the contour of the outer edge of each said section at each side thereof for creating the said depressions, a flange dividing each

depression into two portions, said flange being formed in a continuous curve in an upward and downward direction as shown, said flange extending toward the bottom of the 5 section, there being a recess in the surrounding flange forward of the dividing-flange substantially as shown, there also being a recess in the back of the said surrounding flange behind the dividing-flange, there also being a 10 hole through the sections at each side of the dividing-flange, an opening in the forward portion of the said surrounding flange opposite the upper termination of the said dividing-flange, a hollow water-containing section 15 at each side of the intermediate sections to form the ends of the boiler and the inclosing

members for the fire-space, and corrugations within the fire-space as shown and for the purposes set forth, means for interconnecting all of the sections for intercommunication of 20 water, and a front hollow water-containing member in the front of the sections and having the fire-door opening therein, and means for connecting the front member with the sections for intercommunication of water. 25

In testimony whereof I affix my signature in presence of two witnesses.

JAY B. WALKER.
